US00D898132S

(12) **United States Design Patent** (10) Patent No.: **US D898,132 S**
 Jaquish et al. (45) Date of Patent: ** *Oct. 6, 2020

(54) **EXERCISE APPARATUS**

(71) Applicant: **Jaquish Biomedical Corporation**,
 Nevada City, CA (US)

(72) Inventors: **John Paul Jaquish**, Nevada City, CA
 (US); **Paul Edward Jaquish**, Nevada
 City, CA (US)

(73) Assignee: **Jaquish Biomedical Corporation**,
 Nevada City, CA (US)

(*) Notice: This patent is subject to a terminal disclaimer.

(**) Term: **15 Years**

(21) Appl. No.: **29/734,056**

(22) Filed: **May 8, 2020**

Related U.S. Application Data

(63) Continuation of application No. 35/001,051, filed on Jul. 17, 2015 (U.S. filing date under 35 U.S.C. 384), and having an international filing date of Jul. 17, 2015, which is a continuation of application No. 29/515,595, filed on Jan. 23, 2015, now Pat. No. Des. 778,374.

(57) **CLAIM**

The ornamental design for an exercise apparatus, as shown and described.

DESCRIPTION

FIG. 1 is a first perspective view of an exercise apparatus showing our new design;

FIG. 2 is a second perspective view thereof;

FIG. 3 is a front view of the design of FIG. 2;

FIG. 4 is a rear view of the design of FIG. 2;

FIG. 5 is a side view of the design of FIG. 2, wherein the opposite side of the exercise apparatus is a mirror image of the side view;

FIG. 6 is a top view of the design of FIG. 2;

FIG. 7 is a bottom view of the design of FIG. 2;

FIG. 8 is a first enlarged view of FIG. 1;

FIG. 9 is a second enlarged view of FIG. 1; and,

FIG. 10 is a cross-sectional view taken along the lines of 10-10 of FIG. 8.

The broken lines depict unclaimed environmental subject matter.

1 Claim, 9 Drawing Sheets
